UNITED STATES PATENT OFFICE.

JOHN ALLEN HEANY, OF WASHINGTON, DISTRICT OF COLUMBIA.

SELF-STARTING INTERNAL-COMBUSTION ENGINE.

1,141,633.

Specification of Letters Patent.

Patented June 1, 1915.

Application filed March 27, 1913. Serial No. 757,166.

To all whom it may concern:

Be it known that I, JOHN ALLEN HEANY, a citizen of the United States, and a resident of Washington, in the District of Columbia, have invented certain new and useful Improvements in Self-Starting Internal-Combustion Engines, of which the following is a full and clear specification, reference being had to the accompanying drawings, in which—

Figure 1 is a side elevation of a four-cylinder engine illustrating one form of my invention, parts being shown in vertical section approximately on the line 1—1 of Fig. 3; Fig. 2 is a vertical sectional view, partly in side elevation; Fig. 3 is a horizontal sectional view taken approximately on the line 3—3 of Fig. 2; Fig. 4 a section taken on the line 4—4 of Fig. 2; and Fig. 5 a detailed vertical sectional view taken on the line 5—5 of Fig. 1.

The object of this invention is to so construct the starting mechanism that it shall be built into the engine proper, thereby doing away with the unsightliness, unreliability, lack of durability, and liability to derangement which are necessarily incident to those starting mechanisms which are mere attachments to an engine.

I have illustrated my invention as applied to a well known type of engine (a four-cycle twin-cylinder engine) but it will be understood that the invention is applicable, with modifications as to details, to other types of engines.

In the drawings, *a* designates the usual working pistons, *b* the working cylinders, *c* the pitman connecting the pistons to the main crank-shaft *d*, all constructed in substantially the usual manner. Each piston is extended toward the crank-shaft and provided with a supplemental piston *e* larger in diameter than the main piston and working in a supplemental cylinder *f* formed as a continuation of the main cylinder.

At a point immediately above the lowest point of travel of each supplemental piston *e* each cylinder *f* is provided with a port *g* putting the interior of the cylinder into communication with the atmosphere; and at its upper end each cylinder is provided with a port *h* putting its clearance space *i* in communication with the interior of a valve chest *j* bolted to and extending across all the cylinders. The outer wall of this

valve chamber is provided with two ports *k* which put the interior of the valve chest in communication with a conduit *l* extending to a suitable storage tank *m*, the conduit *l* being provided at a convenient point with a manually operable valve *n* which is adapted to be opened toward the tank *m* and which operates in the manner of a check valve to hold the pressure in the tank.

One of the supplemental cylinders is provided with a supplemental port *o* which puts the clearance space *i* into direct communication with the conduit *l*, a suitable ball or other check valve *p* being arranged in the conduit to normally cut off the pressure in the conduit from the port *o*. In the valve chest *j* is mounted a reciprocating valve *q* which consists of a long bar accurately machined to slide between the outer wall of the valve chest and a machined surface formed on the faces of the cylinders. At the proper points in its length this valve is provided with bearing faces *r* which are adapted to alternately open and close the ports *h* in pairs when the valve is reciprocated. The valve bar is provided with openings *s* at two points, namely, between each outer pair of cut-off faces *r*. Into these spaces lead the respective ports *k*, so that upon reciprocation of the valve so that at all times the interior of the conduit *l* is in communication with the spaces or chambers in the valve chest formed between the two outer cut-off faces *r*.

Entering the valve chest at a point midway the length thereof is a valve shaft *t* and at a point within this valve chest this shaft is provided with an eccentric *u*. This eccentric is connected by a pitman *v* to the valve bar, and this pitman is connected to the bottom wall of the valve chest by means of a retractile spring *w* which exerts a downward pull on the pitman. The shaft *t* carries rigidly one member *x* of a clutch, and slidably mounted on the shaft is the other member *y* of said clutch. A governor *z* is connected to the member *y* of the clutch so as to normally disengage the clutch at a predetermined speed. Affixed to the clutch is a helical gear *a'* which meshes with a helical gear *b'* affixed to the usual cam shaft *c'* of the engine.

Operation: Assuming that air is stored in the tank *m*, to start the engine it is simply necessary to open the valve *n*, whereupon

the compressed air will pass into the two pressure chambers of the valve chest through ports h . From these chambers the air will enter that pair of supplemental cylinders in which the supplemental pistons are ready to descend or have partly completed their downward stroke. As these pistons descend the crank shaft of the engine will be turned and the other pair of pistons will be raised to the upper extremities of their stroke, the air in these cylinders being expelled into the atmosphere through the ports h , one of these exhausting ports h being in communication with the atmosphere through the open end of the valve chest and the other being in communication with the atmosphere through the middle portion of the valve chest and a suitable opening d' formed in the wall of the valve chest, this portion of the valve chest being entirely cut off from those portions of the valve chest subjected to pressure from tank. As soon as the descending pair of pistons reaches the lower extremity of their movement they will exhaust through ports g and also through the upper ports h , the valve g being shifted to uncover the proper ports at the proper time. The shifting of the valve is accomplished by means of the eccentric u , pitman v , shaft t and the connected mechanism. As the pistons e ascend they will complete their exhausting through the upper ports h . After the engine acquires a predetermined speed under air power or full power or both, the governor automatically disconnects the clutch members y and x and also the gears a' and b' , whereupon the valve shaft t is released from the driving power of the engine. When this shaft t is thus released, the downward pull of the spring w exerts sufficient leverage on the eccentric to turn the eccentric downwardly, as shown in Fig. 4, which will cause the valve bar to shift to the position shown in Fig. 4, in which position the cut off faces r close all the ports h against both exhalation and induction of air. As soon as this cut off action takes place the cylinder to which port o is connected commences to act as a pump in recharging the tank m . With each downward stroke of the piston e in this pumping cylinder, the cylinder takes atmospheric air through its port g and upon the ascension of the piston this air is compressed into the clearance i and thence through port o , past valves p and n and on into the tank. This pumping action continues until the maximum pressure is acquired in the tank, this pressure being determined by the cubic volume of clearance i between the upper face of the piston e and the head of this cylinder. After this maximum pressure is obtained this pumping piston e continues to alternately compress and expand the air confined in this cylinder, the cylinder being put into communication with

the atmosphere at the extremity of every down stroke through port g . This alternate compression and expansion of this cylinder air involves no material waste of power, especially in view of the fact that upon each descent of the piston the compressed air will exert its expansive force upon the piston and assist in driving it downwardly; it will thus be seen that the keeping of this pump in continuous operation between the running of the engine can involve but a negligible waste of power, which is more than compensated for by the fact that the restoration of the tank pressure is quickly accomplished without attention on the part of the chauffeur or other attendant.

A feature of importance is that with my construction I need to employ but one of the cylinders for pumping purposes, thus greatly simplifying the mechanism and at the same time providing ample pumping capacity for the restoring of the pressure in the tank. A feature of further importance is that all bother of watching a pressure gage and all danger of obtaining too great a pressure in the tank are avoided since by providing a clearance space above the supplemental piston and providing a port which will put the interior of the supplemental cylinder into communication with the atmosphere at the extremity of the non-compression stroke of the piston, it will be impossible to pump up a higher pressure than that which is provided for in the designing of the engine, this pressure being determined, as stated, by the relation between the cubic volume of cylinder space at the lower extremity of the piston stroke and the clearance space provided for at the upper or compression end of the stroke.

The remaining three non-pumping supplemental pistons will operate in a manner the same as the pumping piston operates after the designed pressure in the tank is attained, namely, alternately compress and expand the air in the supplemental cylinders, each of these cylinders being put into communication with the atmosphere at the lower extremity of the stroke of this supplemental piston. This alternate compression and expansion of the air entrapped in the supplemental cylinders is advantageous in that it serves to cushion the movement of the pistons and thus eliminates noise and wear at the pivotal bearings of the piston rods c .

Having thus described my invention, what I claim as new and desire to secure by Letters Patent, is—

1. In combination with a multiple cylinder explosive engine having enlarged supplemental pistons and cylinders, a port at the upper end of each supplemental cylinder and another port at the lower end thereof, a pressure tank and valved means connecting said tank to said upper ports, and means

operated from the crank shaft of the engine to automatically control said valved means, for the purpose set forth.

2. In combination with a multiple cylinder explosive engine having enlarged supplemental cylinders and pistons connected to the main cylinders and pistons, a storage tank and a conduit connecting the same to ports in the upper ends of said supplemental cylinders, each of said supplemental cylinders being also provided with a port at its lower end adapted to put the interior of the cylinder into communication with the atmosphere upon the down stroke of the supplemental piston working therein, valve mechanism operated from the engine for controlling the ports at the upper ends of the supplemental cylinders, and means whereby when the engine is running on fuel power said valve mechanism will be rendered inoperative, means being provided for converting one of the supplemental cylinders into a pumping cylinder to recharge

the tank when said valve mechanism is thus rendered inoperative.

3. In combination with a multiple cylinder explosive engine having enlarged supplemental pistons and cylinders, a storage tank and means whereby air from said tank may be employed to start the engine through the medium of all said supplemental cylinders and pistons, and means whereby when the engine is running under its own fuel one of the supplemental cylinders will be converted into a pump and will serve to recharge the tank and the remaining supplemental cylinders will alternately compress and expand entrapped air and thus serve as air cushions.

In testimony whereof I hereunto affix my signature in the presence of two witnesses.

JOHN ALLEN HEANY.
